OUTBOARD MOTOR POWERHEAD COWL

Frederick S. Brennan, Evanston, Ill., assignor to Scott-Atwater Manufacturing Company, Minneapolis, Minn., a corporation of Minnesota

Application December 7, 1956, Serial No. 44,116

Term of patent 3½ years

(Cl. D71—1)

Fig. 1 is a side perspective view of an outboard motor powerhead cowl, showing my new design.

Fig. 2 is a side elevational view.

Fig. 3 is a plan view.

Fig. 4 is a rear elevational view.

Fig. 5 is a front elevational view.

I claim:

The ornamental design for an outboard motor powerhead cowl, as shown.
